GARBAGE FILL

John P. Holland, San Francisco, Calif.

Application May 8, 1933. Serial No. 669,993

4 Claims. (Cl. 61—35)

This invention relates to the treatment and use of city refuse for the filling-in of mud flats.

The refuse collected in most cities comprises a large proportion of old paper, cardboard boxes, 5 and the like, as well as food refuse and other fermentable ingredients and other waste products, and the disposal thereof involves considerable expense to many cities.

Many mud flats, due to one cause or another, 10 give off very disagreeable odors, this being sometimes due to deposition of sewage by receding tides in the case of tidelands, so that land, whether natural or filled-in, in the vicinity thereof is undesirable on account of such odors.

15 There are thus two problems presented which appear unrelated to each other, and the main objects of my invention are to solve each of said problems, as well as to solve them in such manner that the solution of each problem contributes to 20 and is co-ordinated with the solution of the other.

Another object of my invention is to make useful disposition of city refuse.

Another object of my invention is to use city refuse in such manner that it will become an 25 asset of value to the city which otherwise had the problem of disposing thereof.

Another object of my invention is to use it in such manner that it will convert a municipal liability into a valuable asset.

30 Another object of my invention is to use such refuse for filling in such mud flats.

Another object of my invention is to do away with the odors arising from such mud flats.

Another object of my invention is to fill in and 35 to make of such mud flats good land useful for ordinary municipal purposes such, for example, as building lots, streets, parks, and the like.

Another object of my invention is to fill in such mud flats with such municipal refuse in such 40 manner that it will not only be odorless, but free of rats, flies and vermin in general.

Other objects of my invention will become apparent on reading the appended specification, taken in connection with the appended drawing 45 which forms a part thereof.

The figure of the drawing is a vertical sectional view of a completed fill made according to my invention.

In some cities no separate storage and collection 50 are made of dry garbage and wet garbage, but all garbage is collected merely as one item. According to my invention, such garbage is thoroughly soaked with water, preferably salt water if available, and a layer thereof about four feet 55 thick is laid at low tide on the mud, this being

rolled with a twelve-ton roller to compress it, thereby reducing it to thickness of about two feet. The refuse may be wetted with the water before or after spreading in layers, as may be desired, but I generally prefer to wet it before spreading. 60 On the drawing the mud is illustrated at 10 and the compressed refuse layer at 11. This layer is then covered with a layer of oil, preferably asphaltic oil, although any oil may be used which will not impart a disagreeable odor when the 65 work is completed and which will tend to repel rats, flies and other vermin. A layer of earth of about six inches to one foot thick is placed thereover, and this is rolled, preferably with a twelve-ton roller, to produce the layer 12. 70

Thereupon, the above set of steps is repeated until the desired height is obtained; that is, a layer of refuse 13 is provided on the layer 12, and layer 13 being similar to the layer 11 and being treated in the same manner by wetting, 75 rolling and oil application, and a layer 14 is provided on the layer 13, this layer 14 being similar to and produced in the same manner as the layer 12. I have illustrated on the drawing only one repetition of such steps, but the number there- 80 of will be determined by the depth of fill desired.

On top of the whole a thickness of earth is placed which will yield a thickness 15 of about two feet when solidly compacted, it being compacted by rolling, preferably with a twelve-ton 85 roller. Thereupon it is rolled with a twelve-ton roller having spikes about six inches long in the wheels thereof, and a surface coat of hot oil is then applied which is allowed to soak in for twenty-four hours; whereupon it is rolled with 90 a twelve-ton roller without spikes which seals the top surface.

The method as described above may be applied to slimy mud flats without causing mud waves as does a heavy rock fill. 95

The salt water is used for the purpose of softening the paper, cardboard, boxes and the like which gives a greater tendency thereto to be compressed and compacted by the roller. Fresh water may be used in place of salt water, but I 100 prefer salt water when available.

Fills on mud flats made according to my method will carry a sixty-ton steam shovel or other object without any indentation of the surface and, in fact, they will carry a locomotive with a 105 train of freight cars loaded to full capacity. A seven-ton truck loaded with seven tons of earth can travel over the surface at a rate of twenty miles an hour.

My invention provides a way for advanta- 110

geously disposing of city refuse as a whole, thereby avoiding the requirement of separating it into or keeping separated the dry and wet components, so that it results in simplifying the collection of the refuse in that both kinds can be stored by the householder in one container and removed in the same conveyance.

In some cities the dry garbage is collected separately from the wet garbage, that is, paper, cardboard, ashes and other solid dry refuse is collected separately from the wet garbage which may contain refuse such as fatty and other food matter, melon rinds, fruit and vegetable pulp or skins, and other like material. However, if certain municipalities should desire to collect the wet refuse and the dry refuse separately, both the wet and the dry may be used according to my invention or, if desired, only the dry refuse may be so used.

20 My invention has an additional advantage for use in districts where there are unimproved and undesired hills, since it provides for disposal of the earth obtained in grading such hills inasmuch as I generally use two tons of earth fill per ton of garbage.

While I have described my preferred method in detail, yet it is to be understood that my invention is not necessarily limited thereto; since changes may be made without departing from the spirit of the invention, the scope of which is defined in the appended claims.

Having described my invention, what I claim is:—

1. The method of filling in mud flats and disposing of municipal refuse containing material made of paper pulp, which comprises providing on said mud flats a substantially four-foot-thick layer of said refuse soaked with salt water, rolling said four-foot-thick layer with a twelve-ton roller to a thickness of two feet, covering said resulting layer with hot asphaltic oil, covering said oiled layer with earth to a thickness of from one-half foot to one foot, then rolling with a twelve-ton roller, building up on said laminated fill so provided by repeating the above mentioned sequence of steps until the desired thickness of fill is attained, locating on top thereof a two-foot-

thick layer of solidly compacted earth, rolling the surface thereof with a twelve-ton roller having six-inch spikes, applying hot oil to the spiked surface and permitting the same to soak in for twenty-four hours, and then rolling the surface with a twelve-ton smooth roller.

2. The method of filling in mud flats and disposing of municipal refuse containing material made of paper pulp, which comprises providing on said mud flats a layer of said refuse soaked with water, compressing said layer, covering the resulting compressed layer with oil, covering said oiled layer with earth, and compressing said earth.

3. The method of filling in mud flats and disposing of municipal refuse containing material made of paper pulp, which comprises providing on said mud flats a layer of said refuse soaked with water, compressing said layer to about one-half its thickness, covering said resulting layer with oil, covering said oiled layer with earth and compressing said earth, building up on said laminated fill so provided by repeating the above mentioned sequence of steps until the desired thickness of fill is attained, then locating on top thereof a layer of solidly compacted earth, perforating the surface of said topmost layer, applying oil to the perforated surface and permitting the same to soak in, and then smoothing over the surface.

4. The method of filling in mud flats and disposing of municipal refuse containing material made of paper pulp, which comprises providing on said mud flats a layer of said refuse soaked with water, rolling said layer to about one-half its thickness, covering said resulting layer with oil, covering said oiled layer with earth, then rolling said earth, building up on said laminated fill so provided by repeating the above mentioned sequence of steps until the desired thickness of fill is attained, then locating on top thereof a layer of solidly compacted earth, rolling and perforating the surface of said topmost layer, applying oil to the perforated surface and permitting the same to soak in for twenty-four hours, and then rolling the surface.
